UNITED STATES PATENT OFFICE.

FRANS BERTIL WENDEL, OF CRANFORD, NEW JERSEY, ASSIGNOR TO HERCULES NOVELTY MFG. CO. INC., A CORPORATION OF NEW JERSEY.

ADJUSTABLE FINGER RING.

Application filed April 22, 1925. Serial No. 25,061.

To all whom it may concern:

Be it known that I, FRANS B. WENDEL, a citizen of the United States of America, and resident of Cranford, in the county of Union 5 and State of New Jersey, have invented a new and Improved Adjustable Finger Ring, of which the following is a full, clear, and exact description.

This invention relates to finger rings and 10 aims for an object to provide an improved means for rendering the ring subject to a wide range of adjustments whereby to fit fingers of various sizes.

The invention furthermore comprehends 15 a finger ring in which the head and shank are constructed as separate elements thereby effecting economy in the manufacture of the ring.

As a still further object the invention 20 templates a ring structure which is simple, inexpensive and efficient.

With the above recited and other objects 25 in view, reference is had to the following specification and drawings in which there is exhibited one example or embodiment of the invention which is in no way intended as a limitation upon the scope of the appended claims as it is to be clearly understood that variations and modifications 30 which properly fall within the scope of said claims may be resorted to when found expedient.

In the drawings—

Figure 1 is a collective perspective view 35 illustrating the head and shank elements of my improved ring in separated condition.

Fig. 2 is a horizontal sectional view illustrating the elements in connected relation for the maximum size of adjustment.

Fig. 3 is a similar view illustrating one 40 of the smaller adjustments to which the ring is subject.

Referring to the drawings by characters 45 of reference, 10 designates the head of the ring and 11 the shank, the former being provided with arcuate diametrically disposed wings or end portions 12 having a plurality or series of keeper openings 13 for receiving the outwardly projecting locking terminals 50 formed by outturned extremities 14 of the shank which shank is of substantially semi-circular formation. The shank 11 is of a resilient material which normally effects a relative spreading separation of the out-

wardly projecting locking terminals 14 to a 55 greater distance than the distance between the wings 12 of the head 10 so that the terminals or extremities 14 are maintained in positive engagement within the keeper openings when the shank is applied to the 60 head. In order to provide means for further preventing rocking movement between the head and shank, the free ends of the wings 12 are provided with inwardly projecting spaced pairs of lugs 15 which snug- 65 ly embrace the edges of the shank 11.

When the head and shank are manufactured, they are assembled by springing the outturned terminals 14 of the shank between the wings 12 to bring the terminals 14 into 70 registry with the keeper openings 13 where the inherent resiliency or springiness of the shank will tend to effect an engagement of the terminals 14 and a retention of the same in the openings 13. At the same time, the 75 portions of the shank adjacent the terminals 14 will be embraced by the lugs 15. Adjustments of the ring size are accomplished by selective engagement of the terminals 14 in the keeper openings 13 so that the ring is 80 capable of adjustment to practically any ordinary finger size required. It is furthermore obvious that the ring size may be reduced after the passage of the ring past the knuckle so that loss of the same is positive- 85 ly precluded.

I claim:

1. An adjustable finger ring comprising two cooperative arcuately curved sections, the end portions of one of said sections having longitudinally spaced series of keeper openings extending in said end portions from their inner faces toward the outer faces thereof, the second section having the extremities thereof turned outward in opposite 90 directions to produce locking terminals adapted to enter and engage with keeper openings of the first section to lock said sections together in adjusted position, said second section being made of material possessing inherent resiliency and the ends thereof being sprung toward each other when the locking terminals of the second section are engaged with keeper openings in the first section so that the spring action of the second section continuously urges the ends of the second section outward against the inner faces of the first section and tends to pre- 95 100 105

vent retraction of the locking terminals of the second section from said keeper openings of the first section.

2. An adjustable finger ring comprising
- 5 two cooperative arcuately curved sections, the end portions of one of said sections having longitudinally spaced series of keeper openings extending in said end portions from their inner faces toward the outer faces
  - 10 thereof, the second section having the extremities thereof turned outward in opposite directions to produce locking terminals adapted to enter and engage with keeper openings of the first section to lock said sections together in adjusted position, said second section being made of material possessing inherent resiliency and the ends thereof being sprung toward each other when the locking terminals of the second section are

engaged with keeper openings in the first 20 section so that the spring action of the second section continuously urges the ends of the second section outward against the inner faces of the first section and tends to prevent retraction of the locking terminals of the second section from said keeper openings of the first section, the end portions of said first section having pairs of lugs at their extremities extending inwardly beyond the inner faces of said end portions of the first 30 section for embracing the end portions of the second section to co-operate with the locking terminals of the second section and with walls of keeper openings of the first section to prevent relative swinging movement of the two sections of the ring. 35

FRANS BERTIL WENDEL.
